United States Patent Office

Des. 205,552

Patented August 16, 1966

205,552

BOTTLE

Willard F. Meyers, Toledo, Ohio, assignor to Owens-Illinois, Inc., a corporation of Ohio

Filed Apr. 1, 1965, Ser. No. 84,550

Term of patent 14 years

(Cl. D58—6)

FIG. 3

FIG. 4

FIG. 1

FIGURE 4 is a fragmentary elevational view partly in section showing the configuration of the top portion of my new design.

I claim:

The ornamental design for a bottle, substantially as shown.
